DESIGN FOR A BOOK READING STAND

Eric S. Leader, New York, N. Y.

Application May 17, 1944, Serial No. 113,637

Term of patent 3½ years

(Cl. D33—10)

To all whom it may concern:

Be it known that I, Eric S. Leader, a citizen of the United States, residing in New York, county and State of New York, have invented a new, original, and ornamental Design for a Book Reading Stand, of which the following is a specification, reference being had to the accompanying drawing, forming part thereof.

Fig. 1 is a top plan view of the book reading stand, showing my new design;

Fig. 2 is a front elevational view; and

Fig. 3 is an end elevational view thereof.

I claim:

The ornamental design for a book reading stand, substantially as shown.

ERIC S. LEADER.
